[57] CLAIM

The ornamental design for a high-resolution video monitor, as shown and described.

DESCRIPTION

FIG. 1 is a top, front and left side perspective view of high-resolution video monitor, showing our new design;

FIG. 2 is a top, rear and right side perspective view thereof;

FIG. 3 is a rear elevational view thereof;

FIG. 4 is a left side elevational view thereof, the right side being a mirror image; and

FIG. 5 is a top plan view thereof.

The bottom view is not seen and constitutes no part of this invention.

*Fig. 1.**Fig. 2.*

*Fig. 3.**Fig. 4.**Fig. 5.*
